Primary Examiner — Paula Greene

(57) **CLAIM**

The ornamental design for audio device, substantially as shown and described.

DESCRIPTION

FIG. 1 is a perspective view of an audio device as seen from the front, top and left side;

FIG. 2 is a front view thereof;

FIG. 3 is a back view thereof;

FIG. 4 is a top view thereof;

FIG. 5 is a bottom view thereof;

FIG. 6 is a right side view thereof; and,

FIG. 7 is a left side view thereof.

The dotted line portions of the drawings represent environmental structure only and do not form part of the claimed design.
